A radial sealing bar for a rotary piston internal combustion engine of trochoidal construction which is guided within an axially parallel groove of a piston and is forced radially outwardly by at least one leaf spring; the sealing bar is thereby provided with at least one hollow space with an opening, into which a leaf spring projects through the opening, whereby the leaf spring rests against the groove bottom in such a manner that the leaf spring is supported against the upper wall portion of the hollow space.

25 Claims, 4 Drawing Figures

FIG. 1**FIG. 2****FIG. 3****FIG. 4**## RADIAL SEALING BAR FOR A ROTARY PISTON INTERNAL COMBUSTION ENGINE

The present invention relates to a radial sealing bar for a rotary piston internal combustion engine, especially of trochoidal type of construction, which is guided in an axially parallel groove of a piston and is pressed outwardly in the radial direction by at least one leaf spring.

It is known to arrange leaf springs underneath the sealing bar in the piston groove between two small leg portions of corner parts of the sealing bar in order to prevent a displacement of the leaf springs in the longitudinal direction of the groove. Such arrangements entail the disadvantage with the use of relatively heavy sealing bars--regardless of whether of one-piece or multi-partite construction--that by reason of the high load of the corner parts by the springs, breakages of the small leg portions which occur frequently cannot be avoided.

The present invention is concerned with the task to eliminate the shortcomings and drawbacks which have occurred in the prior art spring arrangement and to provide a spring construction which additionally enables a lesser assembled structural height of the sealing bar system within the piston groove.

The underlying problems are solved according to the present invention in that the sealing bar is provided with a hollow space having at least one opening, into which the leaf spring resting at the groove bottom of the groove projects through the opening in such a manner that it supports itself at the upper wall portion of the hollow space.

The sealing bar which is constructed hollow, will become lighter by about one-half as regards weight; additionally, it will also become more elastic and impact-resistant. Furthermore, the sensitive small leg portions at the corner parts may be dispensed with because already the hollow space serves as limitation against lateral displacement of the leaf spring.

In order to facilitate the assembly, to prevent the spring from falling out of the sealing bar and additionally to achieve a saving in weight of the sealing bar which is as large as possible, it is proposed according to the present invention that the hollow space extends approximately over the entire length of the sealing bar and in that--as viewed in the longitudinal direction of the sealing bar--two openings or apertures are provided arranged one behind the other, through which extends the leaf spring.

In one advantageous construction according to the present invention, the leaf spring which is bent or curved bow-like, may support itself with its free ends at the upper wall portion in the hollow space of the sealing bar and with its curved portion at the groove bottom of the groove.

Both this arrangement as also the arrangements to be described hereinafter may be used for sealing bars which are constructed either in one piece or are provided with corner parts.

According to the present invention, the leaf spring which is curved or bent bow-like may support itself with its curved or arcuate portion at the upper wall portion in the hollow space of the sealing bar and with its free ends at the groove bottom of the groove.

Only for sealing bars with corner parts provision is made according to the present invention to construct

the leaf spring three-arched in such a manner that the center arc abuts at the upper wall portion in the hollow space and that the adjacent arcs adjoining the center arc are supported at the groove bottom while the free ends of this leaf spring are supported underneath the corner parts.

A lifting off from the casing contact surface or a falling down onto the groove bottom is thus avoided in connection with the corner parts.

It is additionally proposed as a further embodiment according to the present invention for multi-partite sealing parts to provide the corner parts thereof with small leg portions and to arrange underneath the arc of the leaf spring projecting into the hollow space of the sealing bar, a second leaf spring provided with a larger radius of curvature whose free ends are supported at the corner parts in front of or ahead of the respective small leg portions.

Since these small leg portions of this sealing bar system are not exposed to as large loads and stresses, the second spring is constructed relatively weak by reason of the relatively light-weight sealing bar and additionally by the arrangement of the first spring. The second spring has only the task to press the corner parts radially outwardly.

In connection with the two last-mentioned embodiments, friction vibrations and chatter marks are far-reachingingly avoided since the individual sealing bar parts vibrate independently of one another and are thus damped better. Furthermore, the sealing bar parts do not lift off from the casing contact or running surface which means a better gas-tightness of the engine.

For purposes of avoiding scoring and for reasons of better slide properties, the leaf springs are constructed according to the present invention at the free ends thereof so as to be bent either outwardly or inwardly.

Accordingly, it is an object of the present invention to provide a radial sealing bar for a rotary piston internal combustion engine which avoids by simple means the aforementioned shortcomings and drawbacks encountered in the prior art.

Another object of the present invention resides in a radial sealing bar for a rotary piston internal combustion engine which avoids failures in operation, particularly breakages of small leg portions serving as spring abutments.

A further object of the present invention resides in a sealing bar for a rotary piston internal combustion engine which enables a construction of the sealing bar system which is of lesser height within the piston groove.

Still a further object of the present invention resides in a radial sealing bar for a rotary piston internal combustion engine which is considerably lighter in weight, offers greater elasticity and exhibits greater impact resistance than the prior art constructions.

A further object of the present invention resides in a radial sealing bar for a rotary piston internal combustion engine which permits the elimination of the small leg portions, particularly at the corner parts of the radial sealing bar which are sensitive to breaking or other damages.

Another object of the present invention resides in a radial sealing bar for a rotary piston internal combustion engine which facilitates assembly and enables a substantial saving in weight of the sealing bar, yet is simple in construction and easy to install.

A still further object of the present invention resides in a radial sealing bar which far-reachingly avoids frictional vibrations and chatter marks as well as scoring.

These and other objects, features and advantages of the present invention will become more apparent from the following description when taken in connection with the accompanying drawing which shows, for purposes of illustration only, several embodiments in accordance with the present invention, and wherein:

FIG. 1 is a somewhat schematic partial cross-sectional view through a one-piece sealing bar with a leaf spring having a single arc in accordance with the present invention for a rotary piston internal combustion engine;

FIG. 2 is a somewhat schematic partial cross-sectional view through a multi-partite sealing bar in accordance with the present invention provided with corner parts and a single-arched leaf spring;

FIG. 3 is a somewhat schematic partial cross-sectional view through a multi-partite sealing bar in accordance with the present invention with a three-arched leaf spring; and

FIG. 4 is a somewhat schematic partial cross-sectional view through a multi-partite sealing bar with a double spring arrangement in accordance with the present invention.

Referring now to the drawing wherein like reference numerals are used throughout the various views to designate like parts, and more particularly to FIG. 1, a unitary or one-piece radial sealing bar generally designated by reference numeral 1 for a rotary piston internal combustion engine of trochoidal construction which essentially consists of a housing casing 2, of side parts 3 and 4 and of a polygonal piston 5 rotating within these housing parts is illustrated in this figure. Since the rotary piston internal combustion engine of trochoidal construction is of conventional design, a detailed description thereof is dispensed with herein for the sake of simplicity. The sealing bar 1 guided within a groove 6 arranged in the corners of the piston 5 is provided with a hollow space 7 which extends approximately over the entire length of the sealing bar 1. Two openings or apertures 8 and 9 are provided at the bottom side of the sealing bar 1, which serve as passage for a leaf spring 10 bent in the manner of an arc or bow. The free ends 11 and 12 of the leaf spring 10 abut at the upper wall portion 13 within the hollow space 10 of the sealing bar 1 whereas the arcuate portion 14 of the sealing bar 1 is supported at the groove bottom 15 of the groove 6.

The embodiment according to FIG. 2 differs from the embodiment illustrated in FIG. 1 in that the sealing bar 1 is constructed multi-partite and consists of a trapezoidally shaped center part 16—as viewed in longitudinal cross section—, whose shorter one of the two parallel sides is constructed as sealing bar cap or head portion and includes two corner parts 17 and 18. The corner parts 17 and 18 are so formed that they in unison with the center part 16 are pressed radially outwardly against the casing running or contact surface 20 of the housing casing 2 by the spring force, whereby only the center part 16 is provided with a hollow space 19 for the single-arched spring 10.

The sealing bar 1 according to FIG. 3 is provided with a center part 21, again of trapezoidal shape, whose longer one of the two parallel sides—in contrast to the center part 16 of FIG. 2—is constructed as sealing bar

cap or head portion. The center part 21 as well as the corner parts 22 and 23 adjacent the center part 21 are retained by a single three-arched leaf spring 24 which is supported with its centrally disposed arcuate portion 25 at the upper wall portion within the hollow space of the center part 21 whereas it is supported with its two outwardly disposed arcuate portions 26 and 27 at the bottom groove 15 of the groove 6 and with its free ends 28 and 29 at the respective corner part 22 and 23.

The sealing bar 1 according to FIG. 4 is of similar construction as the sealing bar previously described in connection with FIG. 3. The essential difference resides in that the corner parts 30 and 31 of this three-partite sealing bar 1 are provided with small leg portions 32 and 33, respectively. The center part 34 is retained in its position by the leaf spring 10—this spring corresponds to the leaf springs illustrated in FIGS. 1 and 2—whereas for avoiding a lifting off from the casing running surface 20, the corner parts 30 and 31 are forced against the casing contact surface by a second leaf spring 35 bent or curved bow-like, for which the small leg portions 32 and 33 are provided at the corner parts 30 and 31 as lateral limitation or stop. The leaf spring 35 provided with the larger radius of curvature is arranged underneath the first leaf spring 10. Both leaf springs are supported together at the groove bottom 15 of the groove 6.

While I have shown and described several embodiments in accordance with the present invention, it is understood that the same is not limited thereto but is susceptible of numerous changes and modifications as known to those skilled in the art. For example, the free ends of the leaf spring may be bent inwardly or outwardly, as the case may be. Furthermore, the arrangement of FIG. 1 may be reversed so that the arcuate portion of the leaf spring is supported against the upper wall within the hollow space whereas the free ends of the springs are supported in the groove bottom. Such construction is particularly suitable for a one-piece radial sealing bar arrangement. Consequently, I do not wish to be limited to the details shown and described herein but intend to cover all such changes and modifications as are encompassed by the scope of the appended claims.

I claim:

1. A radial sealing bar for a rotary piston internal combustion engine, said radial sealing bar being guided within a groove means of a piston and being forced outwardly substantially in the radial direction by at least one leaf spring means, characterized in that the sealing bar is provided with at least one hollow space having an aperture means, the leaf spring means which abuts at the groove bottom of the groove means projecting into the hollow space through the aperture means in such a manner that the leaf spring means is also supported against the upper wall portion of the hollow space.

2. A radial sealing bar according to claim 1, characterized in that the hollow space means extends approximately over the entire length of the sealing bar and is provided—as viewed in the longitudinal direction of the sealing bar—with two aperture means arranged one behind the other, through which projects the leaf spring means.

3. A radial sealing bar according to claim 1, characterized in that the leaf spring means is constructed three-arched, the center arcuate portion being supported at the upper wall portion of the hollow space

means, the arcuate portions adjoining the center arcuate portion being supported at the groove bottom and the free ends being supported at the sealing bar.

4. A radial sealing bar according to claim 1, of multi-partite construction which includes corner parts, characterized in that the free ends of the leaf spring means are supported under the corner parts.

5. A radial sealing bar according to claim 1, of multi-partite construction which includes small leg portions, characterized in that underneath the arcuate portion of the leaf spring means projecting into the hollow space means of the sealing bar, a further leaf spring means is provided having a larger radius of curvature, whose free ends are supported at the sealing bar ahead of the respective small leg portions thereof.

6. A radial sealing bar according to claim 5, characterized in that the sealing bar includes corner parts provided with said small leg portions and in that the free ends of the further leaf spring means are supported at said corner parts ahead of the small leg portions.

7. A radial sealing bar according to claim 1, characterized in that the free ends of the leaf spring means are bent.

8. A radial sealing bar according to claim 7, characterized in that the free ends of the leaf spring means are bent outwardly.

9. A radial sealing bar according to claim 7, characterized in that the free ends of the leaf spring means are bent inwardly.

10. A radial sealing bar according to claim 1, characterized in that the leaf spring means is curved arcuately shaped.

11. A radial sealing bar according to claim 10, characterized in that the leaf spring means is supported with its free ends at the upper wall portion within the hollow space means of the sealing bar and with its arcuate portion at the groove bottom of the groove means.

12. A radial sealing bar according to claim 10, characterized in that the leaf spring means is supported with its arcuate portion at the upper wall portion in the hollow space means of the sealing bar and with its free ends at the groove bottom of the groove means.

13. A radial sealing bar according to claim 1, characterized in that the rotary piston internal combustion engine is of trochoidal construction.

14. A radial sealing bar according to claim 13, characterized in that the groove means is axially parallel.

15. A radial sealing bar according to claim 14, characterized in that the hollow space means extends approximately over the entire length of the sealing bar and is provided--as viewed in the longitudinal direction

of the sealing bar--with two aperture means arranged one behind the other, through which projects the leaf spring means.

16. A radial sealing bar according to claim 15, characterized in that the leaf spring means is curved arcuately shaped.

17. A radial sealing bar according to claim 16, characterized in that the leaf spring means is supported with its free ends at the upper wall portion within the hollow space means of the sealing bar and with its arcuate portion at the groove bottom of the groove means.

18. A radial sealing bar according to claim 16, characterized in that the leaf spring means is supported with its arcuate portion at the upper wall portion in the hollow space means of the sealing bar and with its free ends at the groove bottom of the groove means.

19. A radial sealing bar according to claim 16, characterized in that the leaf spring means is constructed three-arched, the center arcuate portion being supported at the upper wall portion of the hollow space means, the arcuate portions adjoining the center arcuate portion being supported at the groove bottom and the free ends being supported at the sealing bar.

20. A radial sealing bar according to claim 16, of multi-partite construction which includes corner parts, characterized in that the free ends of the leaf spring means are supported under the corner parts.

21. A radial sealing bar according to claim 16, of multi-partite construction which includes small leg portions, characterized in that underneath the arcuate portion of the leaf spring means projecting into the hollow space means of the sealing bar, a further leaf spring means is provided having a larger radius of curvature, whose free ends are supported at the sealing bar ahead of the respective small leg portions thereof.

22. A radial sealing bar according to claim 21, characterized in that the sealing bar includes corner parts provided with said small leg portions and in that the free ends of the further leaf spring means are supported at said corner parts ahead of the small leg portions.

23. A radial sealing bar according to claim 21, characterized in that the free ends of the leaf spring means are bent.

24. A radial sealing bar according to claim 23, characterized in that the free ends of the leaf spring means are bent outwardly.

25. A radial sealing bar according to claim 23, characterized in that the free ends of the leaf spring means are bent inwardly.
